UNITED STATES PATENT OFFICE.

SIMON BRUNER, OF NEW YORK, N. Y.

DESIGN FOR A RIBBON-CLASP.

59,620.

Specification for Design.

Patented Nov. 15, 1921.

Application filed July 2, 1921. Serial No. 482,230. Term of patent 3½ years.

To all whom it may concern:

Be it known that I, SIMON BRUNER, a citizen of the United States, and a resident of the city of New York, borough of Manhattan, in the county and State of New York, have invented a new, original, and ornamental Design for a Ribbon-Clasp, of which the following is a full, clear, and exact description.

Figure 1 is a top plan view of the ribbon clasp showing my new design;

Fig. 2 is an end elevation of the ribbon clasp; and

Fig. 3 is a bottom plan view of the ribbon clasp.

I claim—

The ornamental design for a ribbon clasp, as shown.

SIMON BRUNER.
